UNITED STATES PATENT OFFICE.

AARON HIGLEY, OF SOUTH BEND, INDIANA.

RAILROAD-CAR BRAKE.

Specification forming part of Letters Patent No. 57,133, dated August 14, 1866.

To all whom it may concern:

Be it known that I, A. HIGLEY, of South Bend, in the county of St. Joseph and State of Indiana, have invented certain new and useful Improvements in Railroad Car-Brakes; and I do hereby declare that the following is a full and complete description of the construction and operation of the same, reference being had to the accompanying drawings, making a part of this specification, in which—

Figure 1 is a top view. Fig. 2 is a side view. Fig. 3 is an end view. Figs. 4 and 5 are detached sections that will be referred to in the description.

Like letters of reference refer to like parts in the several views.

In describing the device of the braking operation at one end it is substantially the same as the other, being constructed and operated exactly alike. When the car is going in the direction indicated by the arrow the windlass G' is used, operating the braking device at the opposite end B', and when going in the other direction the windlass G'' is used, which operates the apparatus at the end B''.

In the drawings, A represents the frame; A', the pedestals in which the shafts *a* of the wheels B have their bearings. C is a framework connected to the shaft of the wheels, and to which some of the apparatus for braking the car is connected, this frame being held in place on the shaft by means of the collars *a'*. On the shaft *a*, and near the center, is a friction-clutch coupling, D, D' being the shell and D'' the cone. To the side of the shell is fastened the ratchet-wheel *b*, the shell and ratchet being permanently attached to the shaft *a* and turning with it, while the cone D'' and pulleys on each side are loose, the clutch-pulleys E E' turning in the opposite direction from the wheels and shell when in operation.

I is a dog pivoted to the pulley E, and one end of which catches in the ratchet *b*.

E is a pulley, close to the ratchet on the shaft *a*, on which the chain *c* is wound. A pulley, E', next to this, from which the chain *d'* is unwound as the spring *d* takes up the slack, which will be referred to in describing the operation.

F is a pulley forming part of the cone which takes up the chain *e*.

F' is a lever, pivoted to the frame at *i*, and is connected to the clutch-lever G by means of the link *f*, the end of the lever G being pivoted at *i'* to the frame, the end clutching round the groove *b'* in the cone, as shown in Figs. 3 and 4, Fig. 4 being a side view with the shaft and wheel cut away.

From the end of the lever F' extends a rope or chain, *g*, to the shaft *f'* of the windlass G', which is turned in braking the car.

H is a bar that rests or has its bearings in the ends of the frame C. Round this bar is coiled the spring H', at the end of which is a swivel, I', to which the chains *c* are connected that wind round the pulleys, as stated, being operated as follows: When it is desired to stop the car the windlass G' is turned, winding the chain *g* around the shaft *f'*. This pulls the lever F' back, thus drawing the end of the clutch-lever to which the link *f* is connected close to the frame C. The other end of the lever, being pivoted to the frame, as stated, forces the clutch along, and this, hitting against the pulley F, forces the cone D'' into the shell D' so tightly and creating so much friction that when the wheels are turning the cone and pulley F of said cone turn with them, when, if the cone was not held so firmly in the shell, it would not turn at all; but as it turns with the wheels the chain *c*, which is attached to said pulley F and the swivel I', will wind round this pulley and the chain *c*, connected to the other side of said swivel, and be taken up by the pulley E, thus contracting the spring H'.

If the pulley E did not turn when the spring H' is contracted the chain *c* would be very slack. To prevent this a spring, *d*, is connected to the side of the frame, and a chain, *d'*, passing round the pulley E', being attached to the end of the spring. As the spring H' is contracted, as described, the spring *d* will contract, unwinding the chain *d'* from the pulley E', thus turning the pulleys E E' in the opposite direction from the wheels, and the slack of the chain *c* will be wound round the pulley E. Thus the spring *d* takes up the slack by contracting, and the end of the dog I will catch in the ratchet *b* by the action of the spring *n* under the other end of the dog, the windlass being held from turning by the ordinary means. Thus the wheels are stopped, not being able to turn in

the least, and a portion of the force expended in braking them is held in reserve, so as to be employed in starting the car after it is stopped.

When the windlass is allowed to turn the spring H' expands in the direction that the car is going, and the clutch-lever will be forced back from the frame by means of a spring, m, in said frame. This lever being forced back, the clutch will move the cone out of the shell again, and the spring H' expanding, the chains connected to the swivel and pulleys will move back with it, thus turning the pulleys on the shaft, and the dog being pivoted to the pulley E and catching in the ratchet b of the shell when the pulleys turn, the dog will aid in turning the wheels. Thus the cars can be started very easily.

In winding up the chains the resistance of the spring as it is contracted tends to stop the

wheels, and in this way the braking of the car is accomplished.

What I claim as my improvement, and desire to secure by Letters Patent, is—

1. The combination of friction-clutch D, pulley F, and clutch-lever G, the dog I, ratchet-wheel b, and pulleys E E', as and for the purpose set forth.

2. The spring H', swivel I', and chains e e, in combination with the chains d' and spring d, as and for the purpose set forth.

3. The clutch-pulleys E E', friction-clutch D, in combination with the ratchet-wheel b and pulley F, substantially as and for the purpose set forth.

AARON HIGLEY.
